UNITED STATES PATENT OFFICE.

JAMES H. TAYLOR, OF WESTFIELD, MASSACHUSETTS.

CHURN-COVER.

SPECIFICATION forming part of Letters Patent No. 380,832, dated April 10, 1888.

Application filed April 4, 1887. Serial No. 233,540. (Model.)

To all whom it may concern:

Be it known that I, JAMES H. TAYLOR, a citizen of the United States, residing at Westfield, in the county of Hampden and State of 5 Massachusetts, have invented new and useful Improvements in Churns, of which the following is a specification.

This invention relates to improvements in devices for securing the heads of churns to the 10 body thereof, the object being to provide for churns having a removable head improved devices for attaching the head thereto; and the invention consists in the peculiar construction and arrangement of said head-fastening devices, as hereinafter fully described, and set 15 forth in the claims.

In the drawings forming part of this specification, Figure 1 is a perspective view of the upper end of the body of a churn having a head 20 provided with fastening devices embodying my improvements. Fig. 2 is a transverse section of the central portion of the head of the churn and of parts of the fastening devices, the latter being hereinafter fully described.

25 In the drawings, A indicates one end of the body of a churn, said body in practice being of a barrel or keg form and belonging to that class of churns in which said body is hung on trunnions and adapted to be rotated for the purpose of agitating its contents.

The head-fastening devices of the churn consist of a metal center piece, o, preferably of circular form, one edge of which is shown broken away in Fig. 1 to show a part of a coiled spring 30 thereunder, and said center piece is shown in cross-section in Fig. 2 through one of three horizontal lever-sockets z thereon and its raised central portion. Said center piece is cast from brass or malleable iron, and has when 35 cast two flat studs standing up on its upper surface, which studs are subsequently bent over to form the hooks x. Said center piece is perforated centrally to provide for placing it on the bolt h in the position shown over the 40 central part of the metal frame f, and is provided with the aforesaid lever-sockets z, across each one of which is fixed a metal bar or rod, n. (See Fig. 2.) A coil-spring, J, is placed on the bolt h between the center piece, o, and 45 the central part of the frame f. Three levers, K, have a hook engagement with said bars n of the three lever-sockets, z, one end of said le-

vers entering said sockets, as shown, and the opposite ends of said levers pass through staples at the border of the head D and engage 55 under the hooks y, secured to the outside of the churn-body, as shown. A toggle-lever, w, having a bifurcated end, is pivotally connected to the upper side of the center piece, o, by having said studs thereon bent over to form hooks 60 x, as aforesaid, which engage with laterally-extending pivot-studs on the legs of said lever w, one of which studs is shown in Fig. 1. Said toggle-lever is provided with two pivot-pins, 5, on its inner opposite sides, and a toggle-yoke, E, of bifurcated form, is perforated, to permit of hanging it loosely on the upper end of the bolt h, its legs pending by the sides of the latter and having notches in their ends, as shown in Fig. 2, to engage with said pivot-pins 70 on the lever w.

The nut s, placed on the end of bolt h, retains the yoke E on said bolt and forms an abutment for the upper end of the yoke, which is capable of such longitudinal adjustment on the bolt as 75 the toggle mechanism consisting of the lever w and said yoke requires to make said mechanism operative to carry the center piece, o, to the position shown in Fig. 1, when the toggle parts are brought substantially into line with 80 said bolt, as shown in said last-named figure.

The spring J serves to lift up the center piece, o, and the ends of the levers K, which engage therewith when the end of the lever w is swung upward, or to the position shown in Fig. 2. 85

When the end of the lever w is elevated, as shown in Fig. 2, the center piece, o, is free to rise by the action of spring J, or to be lifted if no spring is used, and thereby the hook ends of the levers w, connected with said center 90 piece, are so elevated as to cause the opposite ends thereof to lie freely on the border of the head D. While said toggle parts and levers are in the last-described positions, the head is put onto the churn, and being slightly turned 95 thereon the ends of levers w engage under the hooks y on the churn-body. The end of the toggle-lever w is then swung toward the head to the position shown in Fig. 1, thereby depressing the center piece, o, and the ends of the 100 levers connected thereto, and causing the outer ends of said levers to engage with said hooks y, the border of the head serving as a fulcrum on which the levers K act, and hence the

head is thereby forced against the end of the churn-body and remains there fastened until the end of lever *w* is lifted up as aforesaid.

What I claim as my invention is—

- 5 1. A fastening for churn-heads and analogous articles, consisting of the combination, with the head of the churn and with the hooks *y* on the body of the latter, of the center piece, *o*, having sockets in its border, the levers *K*, having one end engaging in said sockets and the other projecting beyond the border of said head, the cam-lever *w*, pivotally attached to said center piece, the yoke *E*, engaging with said lever, and the bolt *h*, fixed to said head and passing through said center piece and yoke, and having the nut *s* thereon, substantially as set forth.
- 10 2. A fastening for churn-heads and analogous articles, consisting of the combination, with the head of the churn and with the hooks *y* on the body of the latter, of the center piece, *o*, having sockets in its border, the spring *J*

beneath said center piece, the levers *K*, having one end engaging in said sockets and the other projecting beyond the border of said head, the cam-lever *w*, pivotally attached to said center piece, the yoke *E*, engaging with said lever, and the bolt *h*, fixed to said head and passing through said center piece and yoke, and having the nut *s* thereon, substantially as set forth. 25

3. In combination with the removable head of a vessel having a bolt, *h*, attached thereto, a center piece, *o*, the levers *K*, having one end engaging with said center piece, a cam-lever, *w*, hung on said center piece, and a yoke, *E*, attached to said bolt, and having a swinging motion thereon and engaging with said cam-lever, substantially as set forth. 30 35
